UNITED STATES PATENT OFFICE.

ERASTUS E. WINKLEY, OF LYNN, MASSACHUSETTS, ASSIGNOR TO THE GOOD-YEAR SHOE MACHINERY COMPANY, OF BOSTON, MASSACHUSETTS.

SOLE-LAYING MACHINE.

SPECIFICATION forming part of Letters Patent No. 557,744, dated April 7, 1896.

Application filed January 14, 1896. Serial No. 575,491. (No model.)

To all whom it may concern:

Be it known that I, ERASTUS E. WINKLEY, residing in Lynn, in the county of Essex and Commonwealth of Massachusetts, have invented certain new and useful Improvements 5 in Sole-Laying Machines, of which the following, taken in connection with the accompanying drawings, is a specification.

The present invention relates to improvements in machines of the above class; and it consists of certain improved mechanisms for relatively actuating the jacks and forms, operating automatically and successively to seat the forms and bring the jacks and forms into 10 a position of pressure, of connections between said mechanisms whereby the operation of the jack-seating mechanism automatically adjusts the pressure mechanism to the height of the shoe upon the sole of which the form is seated, of improvements in the construction and arrangement of the jacks and forms, and 15 of the improved devices and combination of devices, as hereinafter more specifically set forth and claimed.

20 The object of the present invention is to increase the capacity and accuracy of operation of machines of the above-designated class and to eliminate as far as practical therein the liability of injury to the shoe or its last.

25 The present invention is illustrated in the accompanying drawings, in which—

Figure 1 is a front elevation of a machine embodying the same with portion of one of the cams removed to show underlying parts.

30 Fig. 2 is a section on line xx , Fig. 1. Fig. 3 is a rear view, enlarged, of a portion of the carrier and portions of mechanism for seating the form and securing pressure between the form and jack. Fig. 4 is an enlarged

35 plan view, partially in section, showing portions of mechanism for securing pressure between the jacks and forms. Fig. 5 is a side view of said mechanism, portions of the carrier being shown in section on line yy , Fig. 3.

40 Fig. 6 is a detached view of cam actuating the mechanisms for securing pressure. Fig. 7 is a top plan view of one of the jacks. Fig. 8 is a partial plan view showing one of the forms and a portion of the carrier. Fig. 9 is

45 a partial rear view illustrating the stopping

and starting mechanism. Figs. 10, 11, and 12 are detail views of one of the pressing-forms.

Similar letters and figures of reference refer to similar parts throughout the several views.

55 In the drawings, A represents a frame suitable to support the working parts of the machine.

In practice I construct the frame A with a suitable base a , to which are secured the 60 standards a' and a'' . The frame A may be, however, of any other suitable form.

In the frame A is mounted a suitable rotary carrier, conveniently in the form of a spider-frame B, which is arranged to receive 65 a series of partial rotations, for the purposes hereinafter described, stopping automatically and being started at the will of the operator.

A preferred, though by no means essential, form of mechanism for securing the above result is shown in the drawings and described 70 as follows: The spider-frame B is rigidly secured to and rotates with a shaft b , which is mounted and free to turn in suitable bearings in the standards a' and a'' of the frame 75 A.

The shaft b is projected through its bearing in the standard a' and back of the standard a'' carries a worm-gear b' , which is engaged by a worm b^2 on the shaft b^3 . The shaft b^3 is mounted in suitable bearings in 80 the frame A, in which it is free to rotate, and is conveniently driven by means of the usual pulley b^4 . The pulley b^4 turns loosely about the shaft b^3 and is connected therewith by a suitable clutch, mechanism being provided 85

at the control of the operator for engaging the members of the clutch to cause the shaft b^3 and pulley b^4 to rotate together, and automatically-operating mechanisms being provided whereby the members of the clutch are 90 disengaged to stop the rotation of the shaft b^3 and allow the pulley b^4 to turn loosely thereon.

95 While the form of the clutch above referred to or of its actuating mechanism in itself forms no part of the present invention, it may be desirable in this connection to briefly describe the specific form shown and its connection with other features of the machine.

The pulley b^4 being, as before stated, free 100

to rotate independently of the shaft b^3 , is also arranged to slide along said shaft, and the inner face of its hub is provided with a segmental slot, (not shown,) which is engaged by a pin 2 upon a disk 3, which rotates with and is held from motion along the shaft b^3 . (See Fig. 9.) Adjacent to the shaft b^3 is a substantially parallel shaft b^5 , mounted in suitable bearings in the frame A or the brackets 4 thereon, in which it is free to rotate and slide longitudinally, being guided and held in position thereby. On the shaft b^5 is a sleeve 5, free to turn thereon, but held from movement along the same by suitable collars. To the sleeve 5 is secured a fork or collar 6, which engages a groove on the hub of the pulley b^4 . The shaft b^5 also carries a bent lever 7, which turns therewith and is held from motion along the same. The lever 7 by means of a spring 8, secured to an arm 9 on the shaft b^5 and to a fixed part of the machine, or by some other suitable device is normally held in such position that the upper end thereof projects in the path of a series of stops or dogs 10, 10, &c., on the gear b' , the above-described arrangement being such that as the gear b' is rotated one of the stops 10, coming in contact with the lever 7, moves it and the shaft b^5 outward, and by means of the collar 6 moves the pulley b^4 outward, causing the pin 2 to be withdrawn from the segmental slot in the hub of pulley b^4 and allowing the pulley b^4 to rotate independently of the shaft b^3 .

At or near the lower end of the lever 7 is formed a socket 12, which receives the upper end of a rod 14, the lower end of which rests in a socket 15, formed upon the treadle b^6 , fulcrumed at 16 on the frame A, or the lever 7 may be otherwise suitably connected with the treadle b^6 , so that a depression of the treadle b^6 causes the lever 7 to tip backward out of the path of the dog 10. When the lever 7 has cleared the dog 10, a suitably-placed spring 17 closes the clutch, causing the shaft b^3 to rotate with the pulley b^4 , and the spring 8 again advances the lever 7, bringing its front end again into the path of the dogs 10.

The number and position of the dogs 10 will depend upon the number and position of the jacks on the spider-frame. In the form of my invention shown in the drawings, in which the spider-frame is provided with four jacks at substantially ninety degrees apart, I have used four dogs 10 (only two shown) at substantially ninety degrees apart upon the gear b' .

Upon the carrier B are mounted a series of pressing-forms D D, &c., and a series of shoe-supporting jacks E E, &c.

While any suitable pressing-form can be used in combination with the mechanisms herein described without any departure from the present invention, I have in practice adopted a pressing-form which is an improvement upon the form shown and described in the United States Letters Patent No. 549,471,

issued to me November 5, 1895, which, in order that one skilled in the art may readily construct a machine embodying my invention in the best form known to me, I will now describe in detail.

The form D, as shown in the drawings, comprises a rigid bed d, Figs. 10, 11, and 12, having the general longitudinal contour of the bottom of a last, and to which is suitably secured a flexible pressing-pad d'. The pressing-pad d' is formed of a continuous block of rubber or other suitable elastic material and provided with a projected shank portion d² and a reinforcing-strip d³, covering, substantially, the edge-pressing portions of the pad, substantially as shown in my said Letters Patent. Between the shank portion d² of the pad d' and the bed d is located the shank-block d⁴, which bears upon the pad d' at the points d⁵ and d⁶ upon opposite sides of the shank and adjacent to the base of the reinforcing-strip d³. Upon the bed d is formed a boss d⁷, in which is formed a chamber d⁸, which extends through the bed d. To the block d⁴ is secured a stem d⁹, which is fitted to the bore of a tubular threaded bolt d¹⁰, which engages correspondingly-threaded bearings in the top of the boss d⁸. Upon the stem d¹⁰ is a collar d¹², free to slide thereon, and between which and the block d⁴ is placed a coiled spring d¹¹. The inner end of the bolt d¹⁰ bears upon the collar d¹², the above-described arrangement being such that the block d⁴ is held in contact with the pad d' at the points d⁵ and d⁶ by the action of the spring d¹¹, which may be regulated by moving the collar d¹² along the stem d⁹ by turning the bolt d¹⁰ in its threaded bearing. When pressure is applied, the stem d⁹ moves along the bore of the bolt 10 to allow the block d⁴ to be forced toward the bed d, the stem d⁹ acting to guide the block d⁴ and keep it in its proper position. The chamber d⁸ is preferably enlarged at its base to form a recess d¹⁴, which receives the upper portion of the block d⁴, so that the same will not, when forced against the bed d, form a ridge across the form, which would be apt to mar the sole.

The advantages which I claim for a form constructed as above described are its increased accuracy of operation, particularly at the edge portions of the shank, thus insuring an evenly-laid sole and the absence of any ridge or projection in the rigid parts thereof which would tend to mar or otherwise injure the sole.

The jacks E may also be of any suitable construction. I find, however, in practice that a form of jack substantially similar to that shown in the drawings secures the best results, partly on account of the ease and rapidity with which it can be adjusted, but principally because it makes a point upon the shank portion of the shoe a positive point for all sizes of shoes, thereby always bringing the shank portion of the shoe under the same part of the form, a result of great im-

portance in connection with a form having a projected shank portion, as shown in the drawings.

As shown in the drawings, each of the jacks 5 E comprises a toe-rest e and a heel-support e', the bases of which are fitted to a dovetailed groove e² in the base-plate e³, both the toe-rest e and heel-support e' being movable along the plate e³ toward and away from each other.

10 On the plate e³ is eccentrically pivoted a lever e⁴, in the longer arm of which is formed a slot e⁵, (see Fig. 7,) which is engaged by a pin e⁶ upon the toe-rest e or a suitable projection e⁷ thereon. In the shorter arm of the 15 lever e⁴ is formed a slot e⁸, which is engaged by a pin e⁹, secured to a projection e¹⁰ upon the heel-support e'. The above-described arrangement is such that a movement of the toe-rest e along the plate e³ causes a movement of the heel-support e' in an opposite direction and to a less extent, and vice versa. The relative length of the arms of the lever e⁴ determines the relative movement of the toe-rest and heel-support, and since there is 20 a proportional variation in the lengths of the several parts of a sole in the different sizes of shoes it is evident that the lever e⁴ can readily be arranged so that the shank of a large shoe will be brought to substantially the same position under the form as the shank of a small shoe.

25

I am aware that in certain forms of sole-machines it has heretofore been proposed to so arrange the jack that the toe of the last is 30 made a positive point for all sizes, while in others the positive point is at the heel or at the center; but so far as I am aware of the art no jack has been heretofore provided in which a point on the shank is made the positive point for all adjustments for length.

The toe-rest e and heel-support e' as above arranged may be conveniently locked in any desired position by means of a spring-pressed pawl e¹¹, mounted upon the toe-rest e and arranged to engage a series of notches e¹² upon the plate e³.

In all machines embodying a rotary carrier and series of jacks and forms thereon there are three essential movements—first, a rotation of the carrier; second, a relative movement of the jacks and forms from a position of clearance to a position of pressure, and, third, a movement of the jacks out of operative relation to the forms, whereby they are 45 presented to the operator in convenient position for the removal or adjustment of work. I may say in this connection that the jacks and forms are said to be in a "position of pressure" when their relative position is such 50 that the sole of a shoe upon a last placed upon the jack would be sufficiently compressed against the form to properly perform the sole-laying operation and that the jacks and forms are said to be in a "position of 55 clearance" when their relative position is such that the jack can be moved with a shoe

thereon away from the form into a convenient position for the removal of a shoe therefrom.

Having hereinbefore described a preferred form of mechanism for rotating the carrier, 70 I will now describe a preferred form of mechanism whereby the jacks and forms are moved relatively to each other to produce compression and clearance.

In accordance with the present invention 75 the relative movement of the jacks and forms from a position of clearance to a position of pressure occurs in two steps, the first step seating the form firmly on the sole of the shoe upon the jack and the second step bringing the form and jack into a position of pressure—that is, forcing them together with sufficient pressure to successfully perform the sole-laying operation.

The advantage which I gain by dividing 85 the relative movement of jacks and forms as above explained is that I am thereby enabled to use a powerful positively-actuated mechanism for producing pressure, which is automatically adjusted by the seating of the form 90 to the height of the last, and thus, while securing great pressure, to avoid any danger of injury to the last or shoe.

As shown in the drawings, each of the forms D is supported by a swinging lever F, 95 which I have hereinafter called the "form-lever," and which is fulcrumed at f on one of the arms b⁷ of the spider-frame B.

The lever F in practice consists of the substantially parallel arms f' f', (see Fig. 8,) 100 united at one end and at the opposite end embracing a sleeve f² upon the spider-arm b⁷. A trunnion extending through both of the arms f' f' and the sleeve f² secures the lever F to the spider-arm b⁷ and leaves it free to operate, as hereinafter described. The form D is preferably secured to the lever F by a trunnion f³, which is mounted in the arms f' f' and extends through a bearing d¹⁵ in the boss d⁸, (see Fig. 10,) leaving the form D free to 110 tip longitudinally. In practice the bearing d¹⁵ is located substantially over the center of the bed d, and I have provided near each end of the bed d a coiled spring f⁴, (see Fig. 10,) which bears against the bed d and a movable plate f⁵. In the lever F are provided 115 thread-bearings f⁶, which receive the bolts f⁷, the lower ends of which are fitted to sockets in the plates f⁵. Each of the plates f⁵ has upon its under side a circular boss 20, 120 which engages one or more coils of the spring f⁴ and prevents the same from slipping from the plate. A similar boss and for a similar purpose is formed upon the bed d.

The above-described arrangement is such 125 that by turning the bolts f⁷ f⁷ the action of the springs f⁴ f⁴ may be regulated as required, so that the longitudinal tipping movement of form D is controlled by elastic adjustable stops, which is a feature of considerable advantage in this class of machines.

As shown in the drawings, the seating of

each of the forms D is accomplished by means of a spring H, which is secured to the lever F and to the spider-frame B, conveniently at the points h and h'.

- 5 To the standard a^2 of the frame A is bolted or otherwise suitably secured a cam C, the form of which will be hereinafter more fully described, and upon the lever F is secured a cam-roll c or other suitable projection, which, 10 as the spider-frame B rotates, engages the cam C and raises the form D into a position of clearance. As the spider-frame B is further rotated, the cam-roll c leaving the cam C, the spring H, acting upon the lever F, brings 15 the form D down upon the sole of a shoe upon the jack E.

While it is preferable that the form should be firmly seated upon the sole by the spring H, as above explained, it is not intended 20 thereby to secure sufficient pressure to perform the sole-laying operation, although by increasing the strength of the spring H or by substituting therefor a series of springs such 25 operation can be successfully accomplished upon many grades of work and further mechanism for securing pressure dispensed with.

I will now describe in detail the form of mechanism shown in the drawings by which, after the form is seated, I secure the necessary amount of pressure to properly lay the 30 sole.

Reference being had more particularly to Figs. 3, 4, 5, and 6 of the drawings, R represents a link pivotally connected with the lever F, preferably adjacent to its free end, and also pivotally connected with a reciprocating rod r or a suitable offset r', fixedly secured thereon. In practice I have provided a casing r², which is bolted or otherwise fixedly 35 secured to the spider-frame B and in which are provided bearings r³ and r⁴, (see Fig. 5,) in which the rod r is free to reciprocate longitudinally, being guided and held in position thereby. On the rod r is a collar r⁵, free 40 to slide along the rod r and from which is projected an arm r⁶, which is acted upon by a lever r⁷, conveniently pivoted at r⁸ upon the spider-frame B and carrying a cam-roll r⁹, which works upon a cam R', bolted or otherwise 45 suitably secured to the standard a^2 of the frame A. The collar r⁵ is supported by a suitably-placed spring r¹⁰, which may conveniently consist of a coiled spring surrounding the rod r and bearing against the collar r⁵ and the offset r¹¹, projected from the spider-frame B. The rod r extends through the offset r¹¹, and a bearing for the rod r is provided 50 therein.

The above-described arrangement is such 55 that the rod r is free to slide through the collar r⁵ until the lever r⁷ is depressed by the action of the cam R' upon the cam-roll r⁹; but when the lever r⁷ is depressed, as above stated, acting upon the arm r⁶, it cramps the collar r⁵ on the rod r and forces down said rod, for the purposes hereinafter stated.

When the shape of the cam R' permits the cam-roll r⁹ to approach the center and thus relieve the pressure on lever r⁷, the collar r⁵ is no longer cramped, but the rod r is again 70 free to slide through the same, and the collar r⁵ is returned to its original position by the action of the spring r¹⁰. Of course it is understood that the collar r⁵ has a comparatively short bearing on the rod r, and when 75 power is applied away from the rod toward the end of the arm 6 the collar r⁵ becomes cramped or binds on the rod r, forming a positive and easily-controlled clutch which is capable of sustaining great strain without danger of breaking or slipping. To allow for the relative movement of the lever r⁷ and the arm r⁶, I have in practice made the following provision: On the arm r⁶ is a collar l, free to turn thereon, but held from movement 80 along the same. The collar l is provided upon opposite sides with suitable sockets, which are engaged by the inner ends of the thread-bolts l² l², having bearings in a link l', which surrounds the collar l. From the link l' is projected a cylindrical stem l³, which is fitted to a sleeve l⁵ on the lever r⁷. The stem l³ is free to rotate in the sleeve l⁵ and is held in position therein by a suitable collar l⁴. I would say that in practice, the motion of the lever 90 r⁷ being on both sides of the center, the above-described arrangement with the common machine fits will allow sufficient play of parts and is simple and durable.

It is evident that when arranged as shown 100 in the drawings, if the jacks E are empty, the rod r, before pressure is applied, will be moved downward through the collar r⁵ by the action of the spring H, acting through the lever F and link R, until the lever F rests upon the 105 casing r² or some other fixed portion of the machine; and it is further evident that if, when the parts are in the position above stated, the cam R' is allowed to act upon the lever r⁷ to further depress the rod r some part 110 of the machine will be broken or strained.

To avoid the above-stated difficulty, I have provided what I have called a "safety device," and which, as shown in the drawings, consists of a stop R², dependent from the rod 115 r, conveniently from the offset r', and which before the lever F comes in contact with any fixed portion of the machine strikes the collar r⁵ and depresses the same until the arm r⁶, acting upon the lever r⁷, raises the cam-roll r⁹ away from the cam R', so that it cannot be acted upon thereby. The above-described device will be again referred to and its operation more clearly explained in connection with the description of the operation 125 of the machine of the drawings hereinafter given.

The mechanism hereinbefore described as associated with one of the forms being substantially similar to that associated with each 130 of the other forms, no further description thereof is considered necessary herein.

I will now describe the mechanism shown in the drawings whereby the jacks are moyed out of operative relation to the forms.

From the bed-plate e^3 of each of the jacks 5 E are projected the lugs $n\ n$, in which is fixedly secured a shaft n' , having bearings in the projections $n^2\ n^2$ on the spider-frame B. From the base-plate e^3 of each jack E is projected a fixed arm n^3 , the outer end of which 10 (preferably provided with a cam-roll) bears upon a cam N, bolted or otherwise fixedly secured to the standard a' of the frame A. A suitably-placed spring, preferably consisting of a coiled spring n^4 , coiled about the shaft 15 n' and secured thereto and to the spider-frame B, acts to throw the jacks outward and to keep the arm n^3 in contact with the cam N. In practice I make the cam N circular, except at the top, where a depression n^5 is 20 formed. The above-described arrangement is such that as the spider-frame B rotates, the arm n^3 of each jack E, bearing against the cam N, holds the jack in a substantially vertical position under its form D until the 25 arm n^3 falls into the depression n^5 of the cam N, when the spring n^4 forces the jack out of operative relation to its form, presenting it to the operator in convenient position for the removal or adjustment of the work. A further 30 rotation of the spider restores the jack to its vertical position under the form.

In practice I have provided a shelf P at the top of standard a^2 of frame A, which projects over the spider-frame B and affords a convenient and easily-accessible place for the operator to keep his soles while using the machine.

While the specific form of the several cams hereinbefore referred to is by no means an 40 essential feature of the present invention, I will give a brief description of the forms thereof as shown in the drawings, and which I have found in practice to operate successfully.

45 The cam R' may conveniently be formed, substantially as shown in Fig. 6, with an outer circular portion 30 and an inner circular portion 31, connected by the inclined portions 32 and 33. The cam R' is in practice secured 50 upon the standard a^2 , with the inner circular portion at the top and symmetrically arranged with reference to the vertical diameter of the spider-frame B.

The cam N may conveniently consist of a 55 circular disk with the depression n^5 , which when the cam N is in place upon the standard a' is at the top of the cam and symmetrically disposed with reference to the vertical diameter of the spider-frame.

60 The cam C may conveniently be formed with a circular central portion 40 and inclined end portions 41 and 42. When secured to the standard a^2 , the cam C is also symmetrically disposed with reference to the vertical 65 diameter of the spider-frame.

The relative extent of the several portions of the cams above described will be readily

understood from the following description of the operation of the machine.

Assuming the parts of the machine of the drawings to be in the position shown in Fig. 1, the upper form D being in a position of clearance, with its cam-roll c resting upon the circular portion 40 of cam C, and the jack E associated with said form being out of operative relation thereto, with its arm n^3 resting in the depression n^5 of the cam N, and the cam-roll r^9 being upon the inner circular portion of the cam R', so that the rod r is free to slide through the collar r^5 , power being applied to the pulley b⁴, the operator, having removed the finished work and jacked the shoe to be operated upon, places the cemented sole in position and by depressing the treadle b⁶ sets the spider-frame B in rotation. As the 85 spider-frame B rotates, the arm n^3 , being carried out of the depression n^5 onto the circular portion of the cam N, raises the jack E against the action of the spring n^4 and brings it into operative relation to the form D. As soon as 90 this is done the cam-roll c, being carried down the inclined portion 42 of the cam C, allows the spring H to depress the lever F until the form D is seated upon the sole under the pressure of spring H. While the spring H 95 has been seating the form D on the sole it has also, by means of the link R, been depressing the rod r through its collar r^5 . When the form D has been seated as above stated, the rotation of the spider-frame B brings the 100 cam-roll r^9 onto the inclined portion 33 of the cam R', and the lever r^7 being depressed cramps the collar r^5 on the rod r and depresses said rod and the form D until the cam-roll r^9 has reached the outer circular portion 30 of 105 the cam R', when the form is in its position of maximum pressure. It is to be noted in this connection that the mechanism for giving the final motion of pressure to the form D is automatically adjusted for the height of 110 each last and thickness of sole thereon by the seating of the form, so that all lasts, whether high or low, are subjected to an equal amount of pressure, a result of greatest importance in machines of this class. The form D continues in the position of maximum pressure 115 until the rotation of the spider-frame B brings the cam-roll r^9 around to the inclined portion 32 of the cam R', when the lever r^7 is released, releasing the rod r, and the cam-roll c, engaging the inclined portion 41 of the cam C, passes up onto the circular portion 40 of said cam, raising the lever F and bringing the form D into a position of clearance, when the arm n^3 drops into the depression n^5 in the cam N, 120 allowing the spring n^4 to throw the jack E out of operative relation to the form D, and the rotation of the spider stops. When four jacks are used, as in the machine of the drawings, the rotation of the spider-frame B is stopped 125 at every quarter-turn, leaving one form in position of clearance and its jack out of operative relation thereto, while all the other jacks are under pressure. When a different 130

number of jacks is used, a stop is made for each jack, as above explained.

As the operation of the mechanisms associated with each form and jack are substantially the same, the above description is regarded as sufficient.

It is of course understood that the operator removes the work from and adjusts new work upon the jacks successively as they are thrown out of operative relation to their forms.

Should any of the jacks be left empty and the spider-frame B set in rotation, when the cam-roll c reaches the inclined portion 42 of the cam C the spring H acts to depress the lever F, as before described; but before the lever F comes in contact with the casing r^2 , or any fixed portion of the machine, the stop R strikes against the collar r^5 and depresses the same until the cam-roll r^9 clears the cam R', so that while the spider B is making its rotation the cam R' does not act to further depress the rod r.

To adjust any of the jacks E for any length of last, the operator disengages the pawl e^{11} and moves the toe-rest e until the toe-rest e and heel-support e' are in position to properly support the toe and heel of the last, which, without further interference on the operator's part, brings the shank in position to properly receive the projected shank portion of the form D.

Having thus described my invention and its mode of operation, I desire to say that, while shown in the drawings as associated with a sole-laying machine involving a rotary carrier, certain features of the present invention are broadly novel and are not limited in their application to the specific machine shown, since with slight modifications involving no departure therefrom they could be readily adapted to other forms of sole-laying or sole-leveling machines not involving a rotary carrier. I would further say that I have defined the features above referred to, as well as other improvements more particularly applicable to machines having a rotary carrier, in the following claims, upon which I desire to secure Letters Patent of the United States.

50 I claim—

1. In a sole-laying machine the combination of a pressing-form and shoe-supporting jack, mechanism for relatively actuating the form and jack to secure pressure upon the sole of a shoe placed upon the jack, and means for automatically seating the form, in operative connection with said pressure mechanism, and acting to adjust the said pressure mechanism for shoes of different heights, substantially as described.

2. In a sole-laying machine the combination, with a pressing-form and shoe-supporting jack, of mechanism for relatively actuating the form and jack, to secure pressure upon the sole of a shoe placed upon the jack, comprising a reciprocating rod, means for actuating said rod, a collar loose upon said rod,

and suitable connection between said collar and the actuating means for cramping said collar to move the rod, substantially as described.

3. The combination with associated parts of a sole-laying machine, of a pressing-form having a projected shank portion, and a shoe-supporting jack comprising a toe-rest and heel-support movable toward and from each other, and mechanism actuated by the movement of one acting to impart to the other a movement proportionately differing in extent, whereby the shanks of shoes of different sizes are brought into the proper position to receive the projected shank of the form, substantially as described.

4. In a sole-laying machine the combination of a rotating carrier, a series of shoe-supporting jacks mounted upon the carrier, a series of swinging levers fulcrumed upon the carrier, a series of forms supported by said levers, and means for actuating the levers to move the forms from a position of clearance to a position of pressure, substantially as described.

5. In a sole-laying machine the combination, with a shoe-supporting jack, of a swinging lever, a pressing-form supported by said lever and free to tip in the plane of its swinging movement, and elastic stops for limiting the tipping movement of the form, substantially as described.

6. In a sole-laying machine the combination, with suitable pressing-forms, of a rotating carrier, a series of jacks mounted on the carrier and free to tip transversely to the plane of its rotation, a fixed cam, and arms projected from said jacks and arranged to engage said cam, substantially as described.

7. The combination with associated parts of a sole-laying machine, of a suitable pressing-form and a shoe-supporting jack, comprising a heel-support and toe-rest movable toward and away from each other, and an eccentric pivoted lever connecting the heel-support and toe-rest, substantially as described.

8. In a sole-laying machine, the combination of a rotating carrier, a series of jacks mounted upon the carrier, a series of swinging levers fulcrumed upon the carrier, a series of pressing-forms supported by the levers, springs connecting said levers with the carrier, acting to seat the forms, and a fixed cam for raising the levers to bring the forms into a position of clearance, substantially as described.

9. In a sole-laying machine the combination of a jack, a pressing-form, mechanism for relatively actuating the jack and form to secure pressure upon the sole of a shoe upon the jack, a spring and suitable connections acting to seat the form and to adjust said mechanism for shoes of different heights, substantially as described.

10. In a sole-laying machine the combination, with a jack and pressing-form, of connected mechanisms operating automatically

- and successively to relatively actuate the jack and form to seat the form and bring the jack and form into a position of pressure, substantially as described.
- 5 11. In a sole-laying machine the combination, with a jack and pressing-form, of means for bringing the jack and form into a position of clearance, and independently-actuated connected mechanisms operating automatically to relatively actuate the jack and form to seat the form and bring the jack and form into a position of pressure, substantially as described.
- 10 12. In a sole-laying machine the combination, with a rotary carrier, of a series of jacks and pressing-forms mounted thereon, automatic means for relatively actuating each jack and its associated form to seat the form, and mechanism, actuated by the rotation of the carrier, acting after the form is seated to bring the jack and form into a position of pressure, substantially as described.
- 15 13. In a sole-laying machine the combination, with a suitable jack, of a pressing-form comprising a rigid bed having the general longitudinal contour of a last, a continuous elastic pad secured to said bed, a reinforcing-strip for the edge-pressing portions of said pad, a projected shank portion forming part of said pad, and an elastically-supported laterally-concave shank-block interposed between the shank portion of the form and the bed, substantially as described.
- 20 14. In a sole-laying machine the combination, with a suitable jack, of a pressing-form comprising a rigid bed, a continuous elastic pad secured to said bed, a reinforcing-strip for the edge-pressing portions of said pad, a projected shank portion forming a part of said pad, and an elastically-supported shank-block interposed between the shank portion of the pad and the bed, held in contact with the pad, at points adjacent to the reinforcing-strip, upon opposite sides of the shank, and laterally concaved between said points to avoid contact with intermediate portions of the pad, when the pad is not under pressure, substantially as described.
- 25 15. In a sole-laying machine, the combination with a rotary carrier, of a series of shoe-supporting jacks and a series of co-operating forms supported on the carrier, mechanism for producing pressure between the jacks and forms, and means acting during the movement of the carrier to adjust the pressure mechanism, substantially as described.
- 30 16. In a sole-laying machine the combination, with a rotating carrier, of a series of jacks mounted thereon, a series of pressing-forms arranged to co-operate with the jacks, springs and suitable connecting mechanisms for seating the forms, and a fixed cam and suitable connecting mechanisms acting after the forms are seated to bring the forms and jacks into a position of pressure, substantially as described.
- 35 17. In a sole-laying machine the combination, with a rotating carrier, of a series of jacks mounted upon the carrier, a series of pressing-forms arranged to co-operate with the jacks, means for seating the forms, mechanism acting after the forms are seated to bring the jacks and forms into a position of pressure, and a fixed cam and suitable mechanism connected with the jacks whereby the jacks are moved out of operative relation to their forms, substantially as described.
- 40 18. In a sole-laying machine the combination, with a shoe-supporting jack and pressing-form, of mechanism for relatively actuating the jack and form to seat the form upon the sole of a shoe upon the jack, mechanism for securing pressure between the jack and form, and a device, actuated by the seating mechanism, acting to regulate the pressure mechanism to prevent injury to the machine when the jack is empty, substantially as described.
- 45 19. In a sole-laying machine the combination, of a shoe-supporting jack, an elastic pressing-pad, a rigid bed, carrying said pad, substantially centrally pivoted to a suitable support and free to tip longitudinally, and adjustable elastic stops interposed between the bed and its support upon opposite sides of their point of connection, substantially as described.
- 50 20. In a sole-laying machine, the combination with a jack and pressing-form, of mechanism for relatively actuating the jack and form to seat the form, mechanism for producing pressure between the jack and form, an adjustable connection between said mechanisms, and means for automatically adjusting the said connection, substantially as described.
- 55 21. In a sole-laying machine, the combination with a jack and presser-form, of mechanism for seating the form on the jack, mechanism for producing a pressure between the same, a clutch connection between said mechanisms, and connected mechanism operating automatically to release and engage said clutch connection, substantially as described.
- 60 22. In a sole-laying machine, the combination with the jack and form, of mechanisms for relatively actuating the jack and form to produce pressure, and means actuated by said mechanisms and controlled by the work, for regulating the said relative movement between the jack and form, substantially as described.
- 65 23. The combination with the associated parts of a shoe-machine, of a jack comprising a toe-rest and heel-support movable to and from each other, and mechanism actuated by the movement of one acting to impart to the other a movement proportionately differing in extent, substantially as described.
- 70 24. A pressing-form for sole-laying machines comprising a yielding pressing-pad, a rigid bed having a chambered boss, a shank-block having a stem entering the chamber, an adjusting-bolt having a threaded engagement

with the bed, a collar with which the bolt engages, and a spring interposed between the collar and shank-block, substantially as described.

5 25. A pressing-form for sole-laying machines comprising a pressing-pad and bed, of a shank-block, a tubular bolt having a threaded engagement with the bed, a stem entering the bolt and engaging the block, and 10 a spring interposed between the bolt and block, substantially as described.

26. In a sole-laying machine, the combina-

tion with a frame and a rotary carrier, of a jack pivotally mounted on the carrier, a fixed cam with which the jack engages, and means 15 for holding the jack in engagement with the cam, substantially as described.

In testimony whereof I have hereunto set my hand, in the presence of two attesting witnesses, this 10th day of January, 1896.

ERASTUS E. WINKLEY.

Witnesses:

FRED V. HART,
GEORGE E. BARSTOW.
